UNITED STATES PATENT OFFICE.

SAMUEL BERGER, OF NEW YORK, N. Y.

MOTOR MECHANISM FOR MECHANICAL TOYS.

1,393,936.

Specification of Letters Patent.

Patented Oct. 18, 1921.

Application filed June 1, 1921. Serial No. 474,097.

To all whom it may concern:

Be it known that I, SAMUEL BERGER, a resident of New York city, county and State of New York, and a citizen of the United States of America, have invented certain new and useful Improvements in Motor Mechanism for Mechanical Toys, of which the following is a specification.

This invention relates to improvements in motor mechanism, more particularly for mechanical toys. My improvement is directed mainly to improvements in motor mechanism for toys involving a dancing figure, or a figure which has imparted thereto movements to simulate dancing. A further object of my invention is to improve the general construction of this type of mechanism, such for instance as the assembling of the working parts as an entirety and also the assembling of the individual parts. The above mentioned features are directed toward the production of an inexpensive, efficient motor mechanism.

I will now proceed to describe my invention in detail, the novel features of which I will finally point out in the claims, reference being had to the accompanying drawing, wherein:—

Figure 1 is a top plan view of my improved motor mechanism;

Fig. 2 is a sectional end view of the device as illustrated in Fig. 1;

Fig. 3 is a side view, looking from the right in Fig. 2;

Fig. 4 is an enlarged sectional detail view, the section being taken on a line 4—4 in Fig. 1;

Fig. 5 is an enlarged fragmentary sectional view looking from the left in Fig. 2, the section being taken on a line 5—5 in Fig. 2;

Fig. 6 is a fragmentary detail view enlarged, illustrating the propelling device for the spindle which carries the figure;

Fig. 7 is an enlarged sectional detail view, the section being taken on a line 7—7 in Fig. 6; and

Fig. 8 is a fragmentary plan view illustrating the star-wheel which is actuated by the propeller.

The device, as herein illustrated, consists of a box or casing member 9, a portion of which is shown, said box supporting the motor mechanism, indicated generally by 10.

55 The motor mechanism is made up of a frame

member 11, in this instance of channel formation, which supports a train of intermeshing gears 12, 13, 14, 15 and 16 (Fig. 2), the gear 16 being the driving gear which is carried by a rotatable drum 17 surrounded by a spring 18. At one end spring 18 is connected to gear 16 and at the other end to a ratchet wheel 19. The ratchet 19 is carried by a shaft 20 terminating at one end in a handle 21 for winding the spring. The ratchet wheel 19 turns with shaft 20, or in other words is connected to shaft 20 and not to drum 17. When shaft 20 is rotated in the proper direction, spring 18 will be wound up. To hold the spring, after it has been wound up, I provide a double pawl 22 pivotally connected to casing 9 at 23. The pivot 23 is located adjacent one end of the pawl 22, so that end 24 has the long travel. The distance between the teeth of the pawl will be such as to cause the advancing tooth nearest tooth 25 to force end 24 downwardly after said end 24 has been forced upwardly by an adjacent advancing tooth. In other words, the distance 26, between the teeth of the pawl, will be greater than distance 27 between the teeth of the ratchet 19. Consequently the inclined wall 28 of a tooth will force the end 24 of the pawl downwardly. To facilitate this action, the tooth 25 is made longer than the tooth at the end 24 of the pawl. By means of the above construction a spring, to return the pawl, is not necessary.

To hold spring 18 under tension after it has been wound up, or to any time prevent operation of the motor, I provide a brake mechanism consisting of a lever 29 pivoted at 30 to casing 9 and on the inside thereof. The lever at one end carries a nib 31 to engage the teeth of the adjacent gear 12 (in this instance). The upper end of lever 29 projects through an arcuate slot 32 in casing 9 and is provided with a button 33 to enable same to be moved to cause nib 31 to engage the teeth of gear 12 or to clear same. The channeled frame member 11, as can be seen, supports gears 12 to 14, inclusive, and also one end of shaft 20 for ratchet 19, which shaft also loosely supports gear 16, the drum 17, at the end opposite to gear 16, being rotatably supported by the hub 34 on ratchet 19 (see Fig. 4). The frame 11 also supports a vertically movable rotatable spindle 35, which in turn carries the figure to be danced, a portion of such a figure being in-

dicated by 36 (Fig. 2). To impart a rotary and also a vertical movement to spindle 35, I provide a propelling member 37 in the form of arms 38, in this instance formed 5 integral with a plate 39 secured to a cylindrical drum 40 by clips 41 integral with the drum. As can be seen, the clips engage the plate portion 39 of the propeller and are passed over the edges of the plate. The 10 head 42 of the drum is provided with a square opening 43 to fit the square shaft 44 upon which gears 14 and 15 are mounted, said gears being also provided with square openings to engage the shaft 44. After 15 drum 40 and its attached propeller have been applied to the shaft 44, said shaft will be struck up between the end thereof and propeller 37 to form stops 45 and 46. The propelling device will be located between stops 20 45, 46 and the adjacent wall 51 of the frame 11 (see Fig. 7).

To coöperate with propeller 37, I provide spindle 35 with a disk 47 having depressions 49 to receive the end 50 of the wall 51 of 25 frame 11 which does not extend the full length of the frame 11. The disk 47 will be secured to spindle 35. When wheel 47 is in its lowermost position (see dotted lines Fig. 6), the end 50, of wall 51, will engage a depression 49 in the said wheel 47 and will 30 continue to engage a depression until the wheel 47 is raised into alinement with the recess 52 in wall 51 (see Fig. 6). During the rotation of propeller 37, the arms, one at a 35 time, will raise the disk 47 and hence spindle 35 without rotating same until the disk 47 is raised sufficiently to become alined with recess 52, after which it will be rotated during the further movement of the arm 38 in 40 contact therewith. During the movement of an arm from substantially a horizontal position to an approximately vertical position, the shaft 35 will be raised, without being rotated, and then finally rotated. After an 45 arm has cleared the disk 47, the figure and spindle will drop, after which the next arm 38 will repeat the motion above described.

It will be apparent that the figure 36 will have imparted thereto firstly a vertical movement and then a rotary movement, which 50 during the operation of the device will be alternated, producing a very desirable movement on the part of the figure 35.

The motor frame 11 is secured to the casing 9 by means of clips 53 which are passed through openings in the side walls of the casing. The frame 11 acts to brace the casing 9, as well as to support the motor mechanism. When frame 11 is removed, the motor 55 mechanism, excepting gear 16 and its operating spring, will be removed with it. In other words, the frame 11 with its gears, propeller and spindle 35 are a unit that can be assembled and placed in the casing. There- 60 fore, the gears and propelling device need 65

not be built into the casing. This is an advantage from a manufacturing point of view.

What I claim and desire to secure by Letters Patent is:—

1. In a mechanical toy, a longitudinally movable spindle, a disk carried thereby, a rotatable arm arranged for movement in a plane parallel with the spindle, said arm being arranged to contact with said disk and during its movement to move the spindle longitudinally of its axis, means to prevent rotation of the disk during the longitudinal movement of the spindle but to permit the disk to be rotated by the rotary movement 75 of the arm after said spindle has reached the end of its longitudinal movement.

2. In a mechanical toy, a longitudinally movable spindle, a disk carried thereby having recesses or depressions in the periphery thereof, a stop arranged to slidably engage said recesses one at a time to prevent rotation of the disk, and rotary means arranged to contact with said disk to move the spindle longitudinally of its axle until said stop 85 clears the depression in the disk with which it is in engagement, and to impart to said disk a rotary movement after the disk has cleared the stop.

3. In a mechanical toy, a longitudinally movable spindle, a disk carried thereby having recesses or depressions in the periphery thereof, a stop arranged to slidably engage said recesses one at a time to prevent rotation of the disk, and a rotatable arm arranged to contact with said disk to move the spindle longitudinally of its axis until 100 said stop clears the depression in the disk with which it is in engagement, and to impart to said disk a rotary movement after 105 the disk has cleared the stop.

4. The combination of a frame member, having a side wall extending partly the length thereof, a longitudinally movable spindle carried by the frame, a disk carried by the spindle having depressions in the periphery thereof, said depressions being arranged to engage the end of the side wall of the casing, one at a time, to prevent rotation of the disk, said wall having a recess 115 at a point removed from the point of normal contact of the said wall and said disk, a rotatable arm arranged to contact with said disk to move the spindle longitudinally of its axis until said disk reaches the recess 120 in the end wall and to thereafter impart to the disk a rotary movement.

5. The combination of a frame member having a side wall extending partly the length thereof, a longitudinally movable 125 spindle carried by the frame, a disk carried by the spindle having depressions in the periphery thereof, said depressions being arranged to engage the end of the side wall of the casing, one at a time, to prevent rota- 130

tion of the disk, said wall having a recess at a point removed from the point of normal contact of the said wall and said disk, a plurality of rotatable arms arranged to 5 contact, one at a time, with said disk to move the spindle longitudinally of its axis until said disk reaches the recess in the end wall and to thereafter impart to the disk a rotary movement.

10 6. A propelling device consisting of a plate, a plurality of arms integral therewith, a hub member, clips carried thereby to engage the said plate, a head carried by the hub having a square opening, a square 15 shaft engaging said opening, and projections carried by the shaft adjacent the end of the hub carrying said arms to limit the movement of the arms and hub in one direction, and means adjacent the head of the hub to 20 limit the movement of the hub member and arms in the opposite direction.

7. A propelling device consisting of a plate, a plurality of arms integral therewith, a hub member, clips carried thereby to engage the said plate, a head carried by the hub having a square opening, a square 25 shaft engaging said opening, and projections carried by the shaft adjacent the end of the hub carrying said arms to limit the movement of the arms and hub in one direction, and means adjacent the head of the hub to 30 limit the movement of the hub member and arms in the opposite direction, the

projections carried by the shaft being struck up therefrom.

8. In a mechanical toy, a casing, a frame carried thereby to retain a motor mechanism and clips integral with the frame to engage said casing, whereby said frame will act as a brace for said casing.

9. In a mechanical toy, a casing, a frame carried thereby to retain a train of intermeshing gears, a longitudinally movable spindle carried by the frame, a disk carried by the spindle, a plurality of rotatable arms 45 carried by the frame, said disk having recesses in the periphery thereof, a stop carried by the frame to engage said recesses one at a time to prevent rotation of the disk, said rotatable arms being arranged to 50 contact with said disk one at a time and move said spindle longitudinally of its axis until said disk clears said stop and to thereafter impart a rotary movement to the said disk.

10. The combination of a square shaft, a hollow drum carried thereby, a head in said drum at one end thereof having a square opening to receive the square shaft, clips carried by the drum at the opposite end 60 thereof, a motion imparting element engaged by said clips, and means to prevent the drum and its attached motion imparting element from moving longitudinally of the shaft.

SAMUEL BERGER.
